MOTOR VEHICLE

John J. Powers, University City, Mo.

Application October 20, 1947, Serial No. 142,031

Term of patent 14 years

(Cl. D14—3)

To all whom it may concern:

Be it known that I, John J. Powers, a citizen of the United States residing at University City, county of St. Louis, State of Missouri, have invented a new, original, and ornamental Design for a Motor Vehicle, of which the following is a specification, reference being made to the accompanying drawing forming a part thereof, in which Figure 1 is a side elevational view of a motor vehicle embodying my new design; Figure 2 is a perspective view thereof, showing the opposite side to that shown in Figure 1 and also showing the door opened to disclose the interior of the body; and Figure 3 is a rear end elevational view thereof.

The dominant feature of my design resides in the body portion shown in full lines in the drawing.

I claim:

The ornamental design for a motor vehicle, substantially as shown and described.

JOHN J. POWERS.
